UNITED STATES PATENT OFFICE

112,233

DESIGN FOR DECORATIVE PAPER OR SIMILAR ARTICLE

Donald C. Miller, Paterson, N. J., assignor to Frank M. Sayford Co., Inc., Brooklyn, N. Y.

Application April 29, 1937, Serial No. 69,054

Term of patent 3½ years

To all whom it may concern:

Be it known that I, Donald C. Miller, a citizen of the United States, residing at Paterson, in the county of Passaic and State of New Jersey, have invented a new, original, and ornamental Design for Decorative Paper or Similar Article, of which the following is a specification, reference being had to the accompanying drawing, forming a part thereof.

The characteristic feature of the design resides in the arrangement of grass-like elements on corrugated paper as shown.

In the drawing:

Fig. 1 is a plan view of a piece of paper showing my design; and

Fig. 2 is an enlarged view of a section of the paper shown in Fig. 1.

I claim:

The ornamental design for decorative paper or similar article, as shown and described.

DONALD C. MILLER.
